UNITED STATES PATENT OFFICE

162,862

NOSE SYRINGE

Lloyd P. Morton, Great Falls, Mont.

Application April 26, 1949, Serial No. 2,277

Term of patent 3½ years

(Cl. D81—1)

To all whom it may concern:

Be it known that I, Lloyd P. Morton, a citizen of the United States, residing at Great Falls, in the county of Cascade and State of Montana, have invented a new, original, and ornamental Design for a Nose Syringe, of which the following is a specification, reference being had to the accompanying drawing, forming part thereof.

Figure 1 is a front elevational view of a nose syringe, showing my new design;

Figure 2 is a side elevational view thereof, and Figure 3 is a top plan view of the same.

I claim:

The ornamental design for a nose syringe, as shown.

LLOYD P. MORTON.
